PHONOGRAPH PICKUP CARTRIDGE OR SIMILAR ARTICLE

Henry J. Cvetko, Geneva, and Charles J. Chapin, Conneaut, Ohio, assignors to The Astatic Corporation, Conneaut, Ohio, a corporation of Ohio

Application June 10, 1959, Serial No. 56,297

Term of patent 14 years

(Cl. D26—14)

FIG. 1

FIG. 6

FIG. 2

FIG. 3

FIG. 4

FIG. 5

Figure 1 is a perspective view of a phonograph pickup cartridge or similar article, showing our new design;
Figure 2 is a side elevational view;
Figure 3 is a top plan view;
Figure 4 is an opposite side elevational view;
Figure 5 is a front end view; and
Figure 6 is a rear end view thereof.
The bottom has substantially the same appearance as the top shown in Figure 3.

We claim:

The ornamental design for a phonograph pickup cartridge or similar article, as shown and described.
